MATTRESS

Elroy S. Munson, Winnetka, and Solomon L. Pat-
lak and John P. Riley, Chicago, Ill., assignors,
by mesne assignments, to S. Karpen & Bros.,
Chicago, Ill., a corporation of Illinois

Original application July 15, 1935, Serial No.
31,490. Divided and this application December
30, 1938, Serial No. 248,606

4 Claims. (Cl. 5—351)

This invention relates to a mattress.

The present application constitutes a division
of our co-pending application Serial No. 31,490
for Mattress, filed July 15, 1935, which has even-
5 tuated in Patent No. 2,147,348, issued February
14, 1939.

An object of the invention is to provide a mat-
tress of improved construction and in which the
spring core is enclosed within a main casing, and
0 in which flexible cushion structures are attached
to top and bottom sides of the main casing con-
taining a spring core, the attachment being ac-
complished in a novel and efficient manner. A
further object is to provide a mattress structure
5 of sturdy and simple construction which may be
assembled with few operations and at a minimum
of expense. Other specific objects and advan-
tages will appear as the specification proceeds.

The invention is illustrated, in a preferred em-
bodiment, by the accompanying drawings, in
which—

Figure 1 is a broken perspective view of a mat-
tress embodying our invention; Fig. 2, a broken
5 side elevation and part sectional view; Fig. 3, a
view similar to Fig. 2 showing one modification;
Fig. 4, another view similar to Fig. 2, but showing
a second modification; and Fig. 5, another view
similar to Fig. 2 showing a third modification.

In the construction shown in Figs. 1 and 2, A
1 designates a spring structure; B, a main casing
member enclosing the spring structure A and
padding therein; and C, a cushion structure se-
cured to the main casing B.

The spring structure A may be of any suit-
able construction. In the illustration given, it
consists of rows of hour-glass springs 10 con-
nected by helicals 11. If desired, the individual
springs may be enclosed within fabric pockets.

About the spring structure A is folded a blanket
12 of cotton or any suitable filling material.

The main casing B consists of a border strip
13 having its ends stitched to the fabric sheets 14.
Simultaneously with the stitching of the border
fabric 13 to the sheets 14, we stitch the tie strips
15 forming a part of the cushion member C, as
illustrated more clearly in Fig. 2, the stitching
connecting the members 13, 14 and 15, being des-
ignated in the drawings by 15a. The border strip
13 is provided with a padding 16 of cotton or
other suitable material stitched to the strip 13.

In the process of forming the mattress, we first
stitch the ends of border strip 13 together with
the tie strips 15 of the cushion members C to the
main casing sheets 14. Next we place the main
casing upon a filling machine which inserts the

spring structure A together with the filling
blanket 12 thereon to the extent that the main
casing is stretched taut. We next place a cushion
filling material 17 of soft cotton or other
suitable material about the sheets 14 and then
draw fabric cover strips 18 about the filling ma-
terial 17, stitching the ends of the cover 18 and
the fabric strips 15 together and by means of a
binding tape 19.

The structure resulting from the foregoing 10
process affords a taut main casing which snugly
houses the filling and spring core, while at the
same time a soft and flexible cushion body C is
supported about the corners of the main casing.

The mattress may be tufted in any suitable 15
manner. In the illustration given in Fig. 2, the
tufting buttons 20 engage the cushion covers 18,
and the tie members 21 extend through the filling
17, main casing sheet 14, and the inner filling and
spring structure.

If desired, the padded border fabric 13 may be
provided with any suitable number of stitch eye-
lets 22.

The finished mattress will have a taut main
casing snugly enclosing a spring structure, the
terminal or end rings of which extend substan-
tially to the border of the main casing. In con-
trast with the taut main casing, the flexible soft
cushion members C lie on each side of the cas-
ing and may be handled very much as a pillow
or soft cushion. It will be observed, however,
that the tie strip 15, which is secured to the taut
casing 14, confines the outer edge of the cushion
member C so that it is held substantially over
the end or terminal springs of the spring struc-
ture A. By this means, the cushion is supported
in the position shown in Fig. 2.

The border of the main casing may also be
quilted or provided with rolls whereby addi-
tional support is provided for the free edge por-
tion of the cushion C. As shown in Fig. 3, the
padded border may be provided with stitches 23
which form relatively rigid rolls 24 adjacent the
end springs 10, and just below the free edge por-
tion of the cushion C. The tightly drawn main
casing B serves to hold the roll 24 closely against
the end spring and thus provides a compact sup-
porting structure below the edge of cushion C.

In the structure shown in Fig. 4, longitudinal 50
stitches 25 are formed between the eyelets 22 and
drawn so as to bring the eyelets 22 slightly toward
each other, thus forming vertical ribs between
the eyelets 22.

In the structure shown in Fig. 5, both longi- 55

tudinal stitches 25 and vertical stitches 26 are employed to form vertical ribs 27.

While in the illustrations given in Figs. 4 and 5, we have shown two methods of providing vertical fluting or ribs by which the padded border is stiffened to provide a support for the flexible cushion member C, it will be understood that many other means may be employed for this purpose. Instead of one or two rows of eyelets 22, 10 there may be three or more rows, and the eyelets may be drawn together by stitches of any suitable type to provide reinforcing ribs.

The foregoing detailed description has been given for clearness of understanding only, and no unnecessary limitations should be understood therefrom, but the appended claims should be construed as broadly as permissible, in view of the prior art.

We claim:

20 1. In a method of forming a mattress, the steps of stitching the edges of a main casing sheet to one edge of a casing border strip and an edge of a cushion tie strip, stitching the edges of another main casing sheet to the other edge of the 25 casing border strip and an edge of a cushion tie strip to form a casing open at one end, inserting a spring structure enclosed in a filling blanket between said casing sheets and said border strips, closing the open end of said main casing, applying filling material on one side of said main casing, stitching the edges of a cushion cover over said filling material to the edges of the adjacent tie strip, applying filling material on the other side of said main casing, and stitching the edges of the cushion cover thereover to the edges of 30 the adjacent tie strip.

35 2. In a method of forming a mattress, the steps of stitching the edges of a main casing sheet to an edge of a casing border strip and an edge of a

5 cushion tie member, stitching the edges of a second main casing sheet to the other edge of said casing border strip to provide a hollow casing open at least at one end, inserting a spring structure enclosed in a filling blanket within said hollow casing, applying cushion filling material over said main casing, and stitching the edges of a cover to the edges of said cushion tie strip.

10 3. In a method of assembling a mattress, the steps of stitching the edges of a main casing sheet to one edge of a casing border strip and an edge of a cushion tie strip, stitching the edges of another main casing sheet to the other edge of the casing border strip to provide a casing open at one end, inserting a spring structure enclosed in a filling blanket between said casing sheets, closing the open end of said main casing, applying filling material upon said first-mentioned casing and within said cushion tie strip, 15 and stitching the edges of a cover to the edges of 20 said cushion tie strip.

25 4. In a method of the character set forth for forming a mattress having a central spring structure, the steps of stitching the edges of a main casing sheet to one edge of a casing border strip and an edge of a cushion tie strip, stitching the edges of another main casing sheet to the other edge of the casing border strip and an edge of a cushion tie strip to form a casing open at one end, inserting a spring structure between said 30 casing strips and said border strips, closing the open end of said main casing, applying filling material on the outer side of each of said main casings, and stitching the edges of cushion covers over said filling material to the edges of said tie 35 strips.
